UNITED STATES PATENT OFFICE.

LOUIS VINCENT CLAIRE, OF GRAND RAPIDS, MICHIGAN, ASSIGNOR, BY DIRECT AND MESNE ASSIGNMENTS, TO VICTORY RING COMPRESSOR COMPANY, OF GRAND RAPIDS, MICHIGAN, A CORPORATION OF MICHIGAN.

PISTON-RING SQUEEZER.

1,335,367.

Specification of Letters Patent. Patented Mar. 30, 1920.

Application filed August 9, 1919. Serial No. 316,314.

To all whom it may concern:

Be it known that I, LOUIS VINCENT CLAIRE, a citizen of the United States of America, residing at Grand Rapids, in the 5 county of Kent and State of Michigan, have invented certain new and useful Improvements in Piston-Ring Squeezers; and I do hereby declare the following to be a full, clear, and exact description of the invention, 10 such as will enable others skilled in the art to which it appertains to make and use the same.

This invention relates to an appliance for use in squeezing piston rings into the 15 grooves of cylinders so that the same may be readily entered into the cylinders adapted to receive such pistons and rings. Piston rings have a certain tendency to spring outward, this being for the purpose of causing 20 the ring to bear against the inner walls of cylinders and make a tight seal against the passage of mixed air and fuel, or of exhaust gases from above the piston to below the same, and against the passage of 25 lubricating oil from below to the combustion chamber above the piston. This tendency to spring outward normally causes the ring to extend at some points beyond the sides of the piston with a resultant difficulty 30 in placing the piston equipped with rings in a cylinder. It is an object and purpose of the present invention to make a very simple, yet effective appliance with which the rings placed on a piston may be squeezed 35 into position so that the same may easily enter a cylinder and to hold them in such position during the time that the piston is being placed in the cylinder. A further object of the invention is to produce an appliance 40 of this character which may be used with any and all of different sizes of rings and cylinders commonly used with motor vehicle internal combustion engine, working as well with one size as another. Many 45 other objects and purposes, together with novel constructions and arrangements of parts for attaining the same will appear as understanding of the invention is had from the following description, taken in connection 50 with the accompanying drawing, in which,

Figure 1 is a plan view of the appliance as it is used in connection with a piston and

rings, the appliance being in open position ready to squeeze the rings. 55

Fig. 2 is an elevation of the construction shown in Fig. 1, and

Fig. 3 is a fragmentary horizontal section taken through the main squeezing band of the appliance. 60

Like reference characters refer to like parts in the different views of the drawing.

In the construction of the appliance a band 1 of sheet metal is used and bent into approximately circular form, one end overlapping the other, the inner end being indicated at 2. The opposite end is turned outwardly as indicated at 3 and from the upper and lower edges thereof, ears 4 are bent the same lying just outside of the band 1 as shown. From adjacent the inner end 2 of the band for substantially a semi-circumference, hooks 5 are bent from the band both at the upper and lower edges thereof whereby a plurality of spaced pairs of hooks are made between which the outer end of the band passes. It will be noted 70 that the hooks are located relatively close together, in fact that there are six pairs of hooks in what is less than one-half of the length of the band. This relatively close location of the hooks serves an important function in the present construction. Pistons which are used in internal combustion 75 engines are of many different sizes between the smallest size which is approximately two and one-quarter inches in diameter to the largest size which may be about three and three-quarters inches in diameter. All 80 possible dimensions between these two limits are used for pistons in different makes of engines, there being differences as small as one thirty-second of an inch in diameter between different pistons. It follows therefore that a tool of this kind to be of practical utility for use with internal combustion engines must be applicable to each and every possible size between the two limits of sizes one 85 the largest and the other the smallest which 90 this tool can accommodate. Accordingly, a relatively large number of the hooks are used, placed relatively close together so that 95 there is an overlapping of the sizes to which the band may be contracted when the operating handles are engaged with consecu- 100 105

tive pairs of hooks; and the smallest size to which the band may be contracted when the detachable operating handle is engaged with a certain pair of hooks 5 is smaller than the 5 largest size which the band may take when said operating handle is engaged with the next adjacent pair of hooks which are to be used to contract the band to a still smaller size. Likewise the largest size which the 10 band may take when the detachable operating handle is engaged with said certain pair of hooks 5 is larger than the smallest size which the band may be contracted to when engaged with the ears next adjacent to the 15 selected pair of ears which are used for larger sizes of piston, there being an overlapping of the sizes so that any and all of possible sizes of pistons and rings between the two pre-determined largest and smallest 20 sizes may be taken care of by this tool.

Two operating handles 6 and 7 cross each other and are pivotally connected at such crossing point as indicated at 8. The handle 6 beyond the pivot is extended to make an arm 6^a which passes between the ears 4 heretofore described, and the end of the arm 6^a is fashioned with pintles 9 to enter suitable openings in the ears, thus making a pivotal connection therewith. The other 25 handle 7 has an arm 7^a extending beyond the pivot 8 which terminates in an end 10 turned around a pin 11 which is of a length greater than the distance between the upper and lower hooks 5 of any pair of hooks so 30 that the pin may be placed back thereof in the operation of the appliance.

In the use of the appliance, the band is placed around the piston, indicated at 12 at 40 a point where the rings 13 come. I have shown the rings as of the ordinary snap type with a parting at 14 though the invention is capable of use with any of the ordinary kinds of piston rings. In practice the lower ring 13, shown in full in Fig. 2 45 would first be operated on by the appliance, and later the two rings at the upper end of the piston, but in any case the operation is the same. After being placed around a piston and ring or rings, the pin 50 10 is placed back of a pair of hooks 5 and the handles 6 and 7 moved toward each other, this causing a contraction of the band and consequent squeezing of the ring or rings under the band so that the outer surfaces 55 thereof lie in substantially the same planes with the outer surface of the piston. The piston may be inserted in the upper end of a cylinder and when the band 1 comes against the cylinder block it is only necessary to strike the piston on its upper end and thus operate it downwardly through the band, the squeezed ring or rings readily entering the cylinder, as is obvious.

This structure of squeezing appliance may be used with different sizes of pistons and 65 rings, the only difference in operation being that the pin 11 will engage with different hooks 5. The provision of several pairs of hooks 5 spaced apart from each other but close enough together to accommodate any 70 and all diameters of pistons and rings between the smallest and largest sizes which the band will take permits a wide range of use of the appliance as to sizes of pistons. In fact the appliance made in one size is 75 of substantially universal application so far as pistons for internal combustion engines are concerned; and for some engines which make use of larger pistons, there is only need to make the appliance in larger size, 80 in which case a still wider range of use will follow.

The construction is very simple in structure, durable and very efficient in use. It has been thoroughly tried and tested practically and fully serves the purposes for 85 which it is designed.

I claim:

1. An appliance of the character described, comprising a substantially circular metal band having overlapping ends, a handle pivotally connected at its inner end to the outer end of the band, a second handle pivotally connected to the first handle, said handles being pivotally connected 90 at a point between their ends, means on the inner end of the second handle, and a plurality of separate means on the band with which the said means on the handle may detachably engage for contracting the band 100 on operation of the outer ends of the handles toward each other, said second mentioned means on the band being so spaced apart and related to the handles that the band may be contracted to any and all sizes 105 between the largest and smallest size which said band may take when operatively connected with the handles, substantially as described.

2. An appliance of the character described, comprising a flat band adapted to be placed around a piston and cover a ring or rings carried by the piston, said band having overlapping ends whereby it may be used with different sizes of pistons, manually operated means connected to one end of the band, and a plurality of spaced apart hooks on the band near the other end thereof with which said means may have detachable connection, said means being operable 115 to contract the band to any and all sizes 120 between the largest and smallest size of the band, substantially as and for the purposes described.

In testimony whereof I affix my signature. 125
LOUIS VINCENT CLAIRE.
